Inventor.

I. M. Hutchies

UNITED STATES PATENT OFFICE.

IRA M. HUTCHES, OF MARBLE ROCK, IOWA.

FANNING-MILL.

SPECIFICATION forming part of Letters Patent No. 251,443, dated December 27, 1881.

Application filed October 8, 1880. Renewed November 8, 1881. (Model.)

To all whom it may concern:

Be it known that I, IRA M. HUTCHES, of 5
Marble Rock, Floyd county, State of Iowa,
have invented a new and useful Improvement
in Fanning-Mills, which is likewise applicable
to all sorts of grain separating and cleaning
machines which employ a shaking-shoe or
sieve, of which the following is a specification.

The object of my invention is to provide a
means for controlling the "shake" or throw of
the shoe or frame carrying the separating
screens or sieves without waste of force or the
stoppage of the machine; and it consists in the
means hereinafter more particularly set forth.

15. In the accompanying drawing, A is a fanning-mill of the usual shape and structure.

B is the shoe usually forming part of such
machine.

C is a crank-pulley mounted on one end of
20 the fan-shaft, and communicating motion to
the shoe B through a pitman or link, D, elbow-
lever E, mounted upon a bar or bracket, a, se-
cured to the side of the mill, and a link, G,
which at one end is connected to shoe B at any
25 suitable point—preferably at the opposite side
thereof—and at the other end to an eye formed
in or upon a sieve, H, sliding back and forth
upon the arm F of elbow-lever E. The sleeve
and arm fit snugly together, and by prefer-
30 ence are made square or otherwise angular in
cross-section to secure steadiness. It may be
otherwise formed, if desired.

A pivoted link, I, connects the end of the
sliding sleeve H nearest to the pivot of lever
35 E with the inner limb of a hand-lever, K, ex-

tending inward from the fanning-mill casing
about the same distance as the fulcrum of le-
ver E. This lever K is pivoted upon the edge
of the mill-casing where it is cut away for the
shoe, or elsewhere, according to the necessities 40
of various constructions.

Lever K may be moved back and forth, as
shown, to alter as may be desired the mechani-
cal length of the arm F of lever E and the con-
sequent throw (or length of reciprocation) of 45
shoe B. A notched segment, L, fastened out-
side of the mill, serves to secure the lever K
in any desired position.

It is obvious that changes of detail may be
made without departing from the spirit of the 50
invention.

My contrivance permits the alteration or
throw to be effected without stoppage of the
machine.

I claim—

1. The combination of crank-pulley C, link
D, elbow-lever E, sliding sleeve H, link G, and
shoe B with mechanism for adjusting the sleeve
H from the outside of the machine, substan-
tially as and for the purpose set forth. 55

2. The combination of crank-pulley C, link
D, elbow-lever E, sliding sleeve H, suitably
connected to shoe B, and adjusting-lever L,
loosely connected to sleeve H, substantially
as set forth. 60

I. M. HUTCHES.
